UNITED STATES PATENT OFFICE

2,379,856

ELECTRICAL MECHANISM AND WIRING
CIRCUITS THEREFORCharles E. Armstrong, Portland, Oreg., assignor
to Armstrong Heat Control Co., Portland,
Oreg.

Application April 25, 1941, Serial No. 390,292

2 Claims. (Cl. 172—240)

This invention relates to improvements in electrical mechanism and wiring circuits therefor, whereby a control valve, such as is used in steam lines and water lines, can be opened and closed by a two-wire circuit in place of the usual three-wire circuit.

The conventional type of motor-actuated valve which provides for two positions, one open and one closed, is operated by a three-wire circuit in combination with any ordinary timing mechanism operatively associated with the valve actuating gears. In this type of control, a common wire in contact with one of two other wires will cause the valve to close; and this common wire, in contact with the other of said two wires, will cause the valve mechanism to open the valve. In other words, one circuit is completed to the motor for closing the valve; and the breaking of this circuit, and the making of another will cause the valve to move to the open position. This is common practice and has been in use for many years.

In contrast to the foregoing, the principal object of my invention is the provision of simple, efficient, and positive means for opening and/or closing said valve with a two-wire circuit. Closing a supplemental circuit within the two-wire circuit will actuate the motor-driven valve mechanism until a timing mechanism stops the valve in an open position. Breaking the one supplemental circuit and closing another will actuate the motor-driven valve mechanism to return the valve to a closed position.

A further object of this invention is to provide electric means whereby any two-position motorized valve may be opened and then closed with a simple make-and-break type thermostat where heretofore a single-pole double-throw type thermostat must be used on the three-wire circuit control.

The advantages of the two-wire controlling circuit over the common three-wire circuit are numerous in the temperature control field. It will be shown in the drawing how, with a two-wire circuit, any number of thermostats may be installed in a building, and how all of them are connected in parallel on the main two-wire control circuit; and, by this arrangement, any one thermostat can open the valve; but, it requires all thermostats to close the valve.

It will also be shown where, under some requirements, some of the thermostats may be set in series, and others in parallel, thus making the one thermostat placed in series act as a master,

or high-limit control of the other thermostats which are set in parallel.

These and other objects will appear as my invention is more fully hereinafter described in the following specification illustrated in the accompanying drawing, and finally pointed out in the appended claims.

In the drawing:

Figure 1 illustrates the invention operatively applied to a conventional motor and gear mechanism employed in an ordinary two-position motorized valve.

Figure 2 shows an arrangement of thermostatic controls employed to control an indirect heating system.

Referring now more particularly to the drawing:

With reference to Figure 1, reference numeral 1 indicates an electric motor which, through its shaft 2, a worm 3, and worm gear 4, drives a train of gears (not shown) to drive a shaft 5 to which is secured a cam wheel 6. The cam wheel 6 rotates in the direction of the arrow shown, and is formed with a lobe 7. The train of gears driven by the motor 1 through the worm and worm gear is contained within the housing 8, upon which the motor is mounted by means of the bracket 9. The housing 8 is supported upon a bracket 10, which is secured, as at 11, to a valve body 12 disposed within a steam supply line 13, and adapted to control the flow of steam therethrough by means of a valve 14 whose stem 15 is pivotally connected, as at 16, with a link 17. The opposite end of the link is pivotally connected, as at 18, with the cam wheel 6, so that rotation of the cam wheel will impart reciprocal movement to the valve stem 15. In the position shown, the valve is closed; and, upon rotation of the cam wheel 6 through 180 degrees from the position shown will open the valve. The link 17 is preferably of the yieldable type, formed of two halves slidably joined together and having a spring 19 disposed between the halves to compensate for any excessive pull on the valve stem beyond that required to seat the same. The opening and closing movements of the valve are thus controlled by the operation of the motor 1, which rotates intermittently and progressively in one direction, and need not be reversible. A circuit consisting of wires 20 and 21 extends from a source of electrical energy, and the wire 21 connects with the motor 1 at its binding post 22. A branch wire 23 connects with the wire 21 and through binding post 24 to one side of a thermostat 25, having contacts, 26 and 27. The contact 27 connects by

wire 28 through a binding post 29 with one side of a magnet coil 30, whose opposite side is connected by wire 31 with the wire 20, back to the source. The wire 20, by extension 32, connects with one end of an armature 33, forming a part of a single-pole-double-throw switch including contacts 34 and 35 between which operates a contact point 36, carried by the armature. The contact 34 is connected by wire 37 with one arm 38 of a circuit breaker having a companion arm 39. Both arms are yieldingly interconnected by a spring 39A and pivotally mounted, as at 40, to the lower end of the housing 8, and separated by suitable dielectric material. The upper ends of the arms, 38 and 39, carry contacts, 41 and 42, respectively, which are adapted to make and break with contacts 43 and 44, respectively, carried by a buss bar 45 which is mounted to and insulated from the upper end of the housing 8. The buss bar is connected by wire 46 with the opposite binding post 47 of the motor 1. The contact 42 at the upper end of the arm 39 of the circuit breaker is connected by wire 48 with the contact 35 of the single-pole-double-throw switch.

With the parts in the positions shown in Figure 1, the valve 14 has been moved to a closed position by rotation of the cam wheel 6 into a position where the lobe 7 has contacted a projection, or an enlargement 49, on the arm 38 of the circuit breaker which moves that arm to the right, as viewed in Figure 1, and thereby breaks the circuit through wire 31, buss bar 45, and wire 46 back to the motor. Breaking of this circuit, of course, stops motor operation and allows the valve 14 to remain in a closed position to stop the supply of steam to the space being heated until the temperature therein drops to a predetermined degree to cause the contacts, 26 and 27, of the thermostat 25 to come together to close the circuit through wire 23 back to one side of the source, and through wire 28, through the magnet coil 30, thence back to the other side of the source. Energizing the magnet coil, of course, draws the armature 33 and its contact 36 downwardly and away from the contact 34 and into contact with contact 35, whereupon a circuit is then completed from one side of the source through wire 20, through the armature 33, contact 35, wire 48, and through the contact 42 of the arm 39 of the circuit breaker into the buss bar 45, thence through wire 46 into the motor, and from the motor through wire 21 back into the other side of the source. Thus, energy is again supplied to the motor to cause it to operate until the cam wheel 6 rotates again through 180 degrees to move the valve 14 through its stem 15, and the link 17 into an open position. This amount of rotation of the cam wheel 6 also causes the lobe 7 to move out of contact with the arm 38 of the circuit breaker, and into contact with the projection 50 on the arm 39 of the circuit breaker. This contact of the lobe 7, with the projection 50 moves the arm 39 outwardly a sufficient distance to separate the contacts 42 and 43 to again break the circuit to the motor extending through wire 48, contacts 35 and 36, now closed by energization of the magnetic coil 30, thence through wires 31 and 20 back to the source. The opposite side of the motor, of course, is connected with the source through wire 21, running direct to the binding post 22. The opening of the valve 14 will, of course, supply steam for heating the space within which the thermostat 25 is disposed, and will cause the thermostat to resume a satisfied

position, at which time, the contacts 26 and 27 will be separated to break the circuit through wire 23 back to one side of the source, and through wire 28, coil 30, wires 31 and 20 back to the opposite side of the source. Breaking of this circuit de-energizes the coil 30; and by means of the coil spring 51, the armature is swung upwardly around its pivot point 52 into a position to again close the circuit from one side of the source through wire 20, branch wire 32, armature 33, contact 34, wire 37, back into contact 41 of arm 38, then through wire 46 into the motor, the opposite side of which, of course, is connected with the opposite side of the source. Thus a circuit has been re-established to the motor whereby it is again ready to be operated by the demands of the thermostat 25 upon the closing of its contacts, 26 and 27, which will occur upon a drop in temperature.

In Figure 2, I have shown the steam line 13 connected with any approved type of heating coil 53 disposed within an air delivery duct 54 in open communication at its end 55 with a space to be heated. The opposite end of the delivery duct is provided with a suction fan 56 driven by any suitable means, such, for instance, as an electric motor, or the like. The fan housing is in open communication by means of the aperture 57 with an air intake duct 58 extending through the roof or wall of a building to the atmosphere. Operation of the fan will draw fresh air through the intake duct; and by means of the fan, the air will be forced through the heating coil 53, through the delivery duct 54, and into the space to be heated. Within the delivery duct and arranged in advance of the heating coil are two thermostats, 59 and 60. The thermostat 59 may be referred to as a high limit thermostat, and the one at 60 may be referred to as a low limit thermostat. Disposed within the space to be heated is a room thermostat 61. It will be noted that the high limit thermostat 59 is connected in series with a circuit extending to a source of supply consisting of a control circuit C comprising wires 62 and 63 connecting binding posts 64 and 65 which may be the same binding posts 24 and 29, respectively, shown and described in connection with Figure 1, so that the mechanism of Figure 1 may be controlled by any one of the three thermostats 59, 60, and 61 in the indirect heating system. The high limit thermostat 59, being connected in series with circuit C, will render the thermostats, 60 and 61, ineffective at an extremely high temperature, for example, 140° F., at which the thermostat 59 may be set to open. In the temperature range below 140° F., either of the thermostats, 60 and 61, connected in multiple with the circuit C may actuate the valve mechanism to supply more steam to the system. For example, the thermostat 60 may be set to remain closed at any degree below 68, and open at any degree of temperature thereabove, while the thermostat 61 may be set to close at temperatures below 70° F., and to open above that degree of temperature. Thus, if the temperature of the incoming heated air is less than 140° F., and the circuit C is complete up to both thermostats, 60 and 61, by reason of the thermostat 59 being closed, either thermostat, 60 or 61, may retain the steam supply valve 14 in an open position to supply steam to the system, when needed, at their respective locations. For example, if the temperature in the locality of the thermostat 61 is below 70° F., and the thermostat closes, the control circuit will be completed to the binding posts,

64 and 65, and will remain closed until the temperature rises above 70° F., regardless of the attitude of the thermostat 60. If, on the other hand, the temperature in the air delivery duct, which influences the thermostat 60, should drop below 68° F., it will cause the thermostat 60 to close and operate the steam supplying mechanism regardless of the attitude of the thermostat 61.

In Figure 3, I have illustrated a plurality of thermostats 66, 67, and 68, all connected in parallel with a control circuit D, connected with terminals 69 and 70 which may also be the equivalent of the terminals 24 and 29, shown in Figure 1. Each of the thermostats 66, 67, and 68 are of the simple make-and-break type with their contact points so arranged that they will close upon a drop in temperature and open upon a rise in temperature.

Each thermostat may be placed in different remote locations throughout a building or structure to be heated. The purpose of this arrangement is to insure that all parts of the building will be heated to the desired temperature before the steam valve will be closed to cut off the supply of steam. By this arrangement, the part of the building being exposed to a prevailing wind or any other cause necessitating more heat than required in the other parts, the control is automatically established at this point. For example, if the temperature surrounding thermostats 67 and 68 were to rise sufficiently to open the contacts in both of those thermostats, and if the temperature surrounding thermostat 66 remained below the desired temperature, then contacts in that thermostat would remain closed to maintain the circuit closed through binding posts 69 and 70 which, in turn, through the mechanism described in Figure 1, will hold the steam valve in an open position to continue the supply of steam. But, when the temperature surrounding the thermostat 66 is brought up to open those contacts, the control valve will then close. Thus, a temperature drop at the location of any of the thermostats, 66, 67, 68, or any number of them so connected in the control circuit will pick up the control of the steam valve.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

1. An electrically operated device, comprising an electric motor, a gear mechanism, two mechanically operated electric switches, an electric relay having two switches; one of said relay switches being normally open; the other of said relay switches being normally closed; two electric circuits, a thermostat disposed at a remote station, said motor operating said gear mechanism, said gear mechanism operating said two mechanically operated switches, said electric relay being operated by said remotely stationed thermostat, said motor and said two mechanically operated switches and said two relay operated switches being embraced within one of said electric circuits, said relay and said remotely stationed thermostat being embraced within the other of said electric circuits.
2. An electrically operated device, comprising an electric motor connected in a circuit to a source of electrical supply through an electric relay, said relay also being connected to said source of supply and having two switches associated therewith and operable thereby, a pair of switches operatively connected with said motor and adapted to be opened and closed thereby, said pair of switches being electrically connected with the switches of the relay whereby, current from the source may be alternately directed to the motor by operation of the relay switches, a two-wire circuit extending from the relay to a temperature sensitive switch remotely disposed from the device to the source of supply whereby closing or opening of said switch will actuate the relay to direct current to the motor for a predetermined length of time.
